ARTICULATED VEHICLE

Jack D. McCawley, Pratt, Kans.
(P.O. Box 65, Mullinville, Kans. 67109)

Filed Feb. 17, 1969, Ser. No. 15,791

Term of patent 14 years

Int. Cl. D12—09

U.S. Cl. D14—3

FIG. 1

FIG. 2

FIG. 3

FIG. 4

FIG. 1 is a side perspective view of an articulated vehicle embodying the design of my invention;

FIG. 2 is a perspective view of the opposite side of the vehicle;

FIG. 3 is a rear perspective view of same; and

FIG. 4 is a front perspective view of the vehicle.

I claim:

The ornamental design for an articulated vehicle, as shown.
